UNITED STATES PATENT OFFICE.

JOHN FORD, OF PORTNEUF, QUEBEC, CANADA.

HOSPITAL-BED.

1,318,271.

Specification of Letters Patent.

Patented Oct. 7, 1919.

Application filed October 26, 1918. Serial No. 259,870.

To all whom it may concern:

Be it known that I, JOHN FORD, a citizen of the Dominion of Canada, and a resident of Portneuf, in the Province of Quebec and 5 Dominion of Canada, have invented a new and Improved Hospital-Bed, of which the following is a full, clear, and exact description.

This invention relates to hospital beds, 10 operating tables, stretchers and the like, and it has to deal more particularly with a flexible bed bottom or table top having a recess or well for enabling bandages to be easily applied and sheets to be changed without 15 altering the position of the patient, and also to accommodate a bed pan or the equivalent.

The invention has for its general objects to improve the construction of devices of this character so as to be reliable and efficient 20 in use, comparatively simple and inexpensive to manufacture, and so designed as to more comfortably accommodate a patient.

A more specific object of the invention is the provision of a flexible bed bottom, table 25 top or the like which has an adjustable recess or well which can be moved to any point within the length of the bed bottom or table top to facilitate operating on or bandaging the patient or for changing the 30 sheets, or for accommodating a bed pan, the said recess being formed by a movable frame or carriage slidably mounted on the bed, stretcher or table frame and having guide rollers whereby a loop is formed in 35 the bed bottom or table top to constitute the well or recess.

With such objects in view, and others which will appear as the description proceeds, the invention comprises various novel 40 features of construction and arrangement of parts which will be set forth with particularity in the following description and claims appended hereto.

In the accompanying drawings, which 45 illustrate one embodiment of the invention and wherein similar characters of reference indicate corresponding parts in both the views.

Figure 1 is a vertical longitudinal section 50 of a hospital bed equipped with the invention; and

Fig. 2 is a plan view thereof.

Fig. 3 is a longitudinal vertical sectional view through a slightly modified form of 55 bed from that disclosed in Fig. 1.

Fig. 4 is a fragmentary horizontal sec-

tional view through Fig. 3 on line 4-4, illustrating the arrangement of the rollers and support at the end of the body.

In the present instance the invention is 60 shown as a hospital bed, but it is to be understood that it may be applied to a stretcher, operating table or the like.

Referring to the drawings 1 and 2 designate the head and foot of a bed connected by 65 the usual side bars 3.

The bed bottom comprises a strip of canvas 4 fastened at its ends to head and foot cross bars 5 and 6 which are secured to the bed frame. On this canvas may be arranged 70 a thin mattress 7 over which is a sheet 8. The bed bottom formed by the canvas and the mattress is considerably longer than the length of the bed, so that a hanging loop is provided at 9 to constitute a recess or well 75 10 in the bed bottom. This well is held open by the use of a plurality of spaced upper rollers 11 and 12 and spaced lower rollers 13 and 14, all of such rollers being mounted on a frame or carriage 15 having wheels 16 80 that ride on the side bars 3. The upper rollers 11 and 12 have their journals extended into squared extremities 17 for receiving an operating crank 18 whereby the roll-carrying frame 15 can be moved from 85 one end of the bed to the other to thereby adjust the position of the well or recess 10. This well permits a patient to be operated on or treated more conveniently, and enables 90 bandages to be more readily applied and sheets to be changed without altering the position of the patient. In Fig. 2 of the drawing a second sheet 8^a is shown near the foot just in the act of being spread on the bed bottom and the sheet 8 being removed. The 95 frame 15 includes a horizontal trough-like member 15^a which serves to form the body of the well to hold the sheets as well as a bed pan or the like. As the carriage or frame 15 is moved toward the head the sheet 100 8^a will be spread on the bed bottom and the sheet 8 will wind up in the well.

In Fig. 3 will be seen a slightly modified form of bed in which a chain flexible cable or other connecting means 19 is provided to hold the auxiliary rollers 20 in place, said auxiliary rollers resting on the side rails 3 of the bed and guided on to said rails and over said rails by guiding members 21 arranged at each end of the bed. This may 110 be readily accomplished as seen in Fig. 4 when the side rail 3 is connected to a suitable

arm projecting from the leg or upright of the bedstead. The same carriage may be used in this form of the invention as in the preferred form, or the same carriage with 5 one of the rollers removed as preferred. This construction and arrangement of rollers 20 produces a firm and comparatively rigid support so that the bed may be used as an operating table if desired in addition 10 to that of a bed. The head or pillow support 22 is bolted or otherwise rigidly secured to the angle iron 5 and may not only be used in this form of the invention but in the preferred form without departing from the 15 spirit of the invention.

In the following claims the term "supporting structure" will be understood to cover a bed frame, stretcher frame or table frame, and the term "flexible element" will 20 cover a bed bottom, stretcher canvas, operating table top, or the like.

From the foregoing description taken in connection with the accompanying drawings, the advantages of the construction and 25 method of operation will be readily understood by those skilled in the art to which the invention appertains, and while I have described the principle of operation, together with the device which I now consider to be the best embodiment thereof, I 30 desire to have it understood that the device shown is merely illustrative and that such changes may be made when desired as fall within the scope of the appended claims.

35 Having thus described my invention, I claim as new and desire to secure by Letters Patent:

1. A hospital bed comprising a support, a 40 flexible bedding member having its ends fastened to said support and provided with a loop intermediate its ends to constitute a well or recess, and a movable frame on the said structure for holding the loop open.

2. A hospital bed comprising a support, a 45 flexible element having its ends fastened to said support and provided with a loop intermediate its ends to constitute a well or recess, and a frame on the said support for holding

the loop open, said frame being movable to change the position of the said well. 50

3. A hospital bed comprising a support including side bars, a carriage movably mounted on the side bars, a pair of spaced upper rollers on the carriage and a pair of lower rollers on the frame, and a flexible 55 element fastened to said support and extending successively over one of the upper rollers, under the lower rollers and over the other upper roller, whereby a recess or well is formed. 60

4. A hospital bed comprising a support including side bars, a frame movably mounted on the side bars, a pair of spaced upper rollers on the frame and a pair of lower rollers on the frame, said upper rollers resting on 65 said bars, a flexible element fastened to said support and running successively over one of the upper rollers, under the lower rollers and over the other upper roller, whereby a recess or well is formed, and a trough-like member 70 located on the frame at a point between the lower rollers.

5. A hospital bed comprising a supporting bed frame, a flexible element in the form of a strip having its ends fastened to said 75 frame, the length of the element being longer than the frame, whereby a loop is provided within the length of the element to constitute a well or recess, and a movable carriage supported by said frame for holding the 80 loop open and for permitting the loop to be moved to any part of the frame.

6. A hospital bed comprising a supporting structure, a flexible element in the form of a strip having its ends fastened to the supporting 85 structure, the length of the element being longer than the supporting structure, whereby a loop is provided within the length of the element to constitute a well or recess, movable means for holding the loop open 90 for permitting the loop to be moved to any part of the supporting structure, and flexible supporting means positioned beneath said flexible element for supporting the same. 95

JOHN FORD.
